(57) **CLAIM**

The ornamental design for a lash application device, as shown and described.

DESCRIPTION

FIG. 1 is a perspective view of the lash application device in full lines.

FIG. 2 is a top plan view of the lash application device.

FIG. 3 is a bottom plan view thereof.

FIG. 4 is a right side elevational view thereof.

FIG. 5 is a left side elevational view thereof.

FIG. 6 is a front elevational view thereof.

FIG. 7 is a rear elevational view thereof; and,

FIG. 8 is a second perspective view of a lash application system comprising the lash application device in full lines with a cosmetic pick and a set of tweezers in broken lines representing environmental association matter being for illustrative purposes only and forming no part of the claimed invention.

The broken lines along the front surface of the device illustrate a portion of the article and form no part of the claimed design.
